(57) **CLAIM**

The ornamental design for a wearable lighting device, as shown and described.

DESCRIPTION

FIG. 1 is a front perspective view of a wearable lighting device showing the new design;

FIG. 2 is a rear perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front side elevational view thereof; and

FIG. 8 is a rear side elevational view thereof.

FIG. 9 is a front perspective view of the wearable lighting device with an example wrist strap attached thereto; and, FIG. 10 is a rear perspective view thereof.

The dashed broken line showing represents portions of the article not claimed and forms no part of the claimed design. The dot-dash broken line showing defines the bounds of the claimed design and forms no part thereof.
